Primary Examiner—Stella Reid*Attorney, Agent, or Firm*—Dorr, Carson, Sloan & Peterson[57] **CLAIM**

The ornamental design for a video fluoro imaging chair for dysphagia studies, as shown and described.

DESCRIPTION

FIG. 1 is a perspective view of a video fluoro imaging chair for dysphagia studies, showing my new design, the broken line showing is for illustrative purposes only and forms no part of the claimed design;

FIG. 2 is a front elevational view thereof;

FIG. 3 is a right side elevational view thereof, the left side elevational view being a mirror image thereto;

FIG. 4 is a rear elevational view thereof;

FIG. 5 is a top plan view thereof; and,

FIG. 6 is a bottom plan view thereof.
